[57] CLAIM

The ornamental design of a flush pin gage base, as shown and described.

DESCRIPTION

FIG. 1 is an elevational view of a flush pin gage base illustrating my new design, the opposite side being a mirror image thereof.

FIG. 2 is a bottom view thereof.

FIG. 3 is a top view thereof.

FIG. 4 is a view as seen from the right end of FIG. 1, the opposite side being a mirror image thereof; and,

FIG. 5 is a sectional view as seen along lines 5—5 of FIG. 1 to illustrate the diamond-shaped surface configuration.
